US00D553127S

(12) **United States Design Patent** (10) **Patent No.:** **US D553,127 S**
Burns (45) **Date of Patent:** **** Oct. 16, 2007**

(54) **PORTION OF A HANDSET**

(75) Inventor: **Duncan Burns**, Tarzana, CA (US)

(73) Assignee: **Nokia Corporation**, Espoo (FI)

(**) Term: **14 Years**

(21) Appl. No.: **29/270,761**

(22) Filed: **Jan. 4, 2007**

Related U.S. Application Data

(62) Division of application No. 29/216,098, filed on Oct. 28, 2004, now Pat. No. Des. 544,851.

(51) **LOC (8) Cl.** **14-03**

(52) **U.S. Cl.** **D14/248**

(58) **Field of Classification Search** **D14/138, D14/341-347, 147-148, 496, 137, 248, 218; 379/433.01-433.13; 455/566, 575.1, 556.1, 455/556.2, 90.3; D21/517, 329, 331**

See application file for complete search history.

CLAIM

The ornamental design for a portion of a handset, as shown and described.

DESCRIPTION

FIG. 1 is a portion of a handset showing my new design;

FIG. 2 is a right side view thereof;

FIG. 3 is a front view thereof;

FIG. 4 is a left side view thereof;

FIG. 5 is a top view thereof;

FIG. 6 is a rear view thereof;

FIG. 7 is a perspective front view thereof; and,

FIG. 8 is a perspective rear view thereof.

The broken lines shown in FIGS. 1-8 that are immediately adjacent to the shaded areas represent the bounds of the claimed design, while all other broken lines are directed to environment and are for illustrative purposes only; the broken lines form no part of the claimed design.

1 Claim, 4 Drawing Sheets
